UNITED STATES PATENT OFFICE.

CHARLES H. BEELER, JR., OF PHILADELPHIA, PENNSYLVANIA, ASSIGNOR
TO THE MACKELLAR, SMITHS & JORDAN COMPANY, OF SAME PLACE.

DESIGN FOR A FONT OF PRINTING-TYPE.

SPECIFICATION forming part of Design No. 17,125, dated February 22, 1887.

Application filed January 26, 1887. Serial No. 225,538. Term of patent 14 years.

To all whom it may concern:

Be it known that I, CHARLES H. BEELER, Jr., (assignor to the MACKELLAR, SMITHS & JORDAN COMPANY,) of the city and county of 5 Philadelphia, Pennsylvania, have invented a new and original Design for a Font of Printing-Type, of which the following is a specification.

The nature of my design is clearly shown 10 in the accompanying typographic impression, to which reference is made; and it consists of an unshaded letter.

The central ornament of the A consists of 15 the two inclined lines extended beyond the up and down portions and meeting at a central point. The lower right-hand portion of the B, K, and R is extended above the upper right-hand portion of the letter, and is joined upon the left by the short inclined line. The upper 20 right-hand termination of the C and G consists of the short inclined line extending above and below the upper portion of these letters. In the E, F, and K the upper right-hand portion is ornamented by the short inclined line 25 extending below the upper portion of the letters. In the E, L, and Z the lower right portion of the letters is followed by the short inclined line extending above and below this portion of the letters. The central ornament 30 of the H consists of the two short inclined lines crossing each other about centrally. The lower left-hand portion of the J is widened at its upper termination and crossed by the short inclined line. The connecting portion of the 35 M consists of the two inclined lines forming about centrally the open triangular ornament. Upon the lower right hand of the N is found the short inclined line termination. The tail of the Q consists of an inclined line with short 40 inclined line at each end, one (the left) below and the other (the right) above the line. In the S both the inclined-line terminations are extended above and below the portions of the letter they ornament. In the W the central 45 portion of the letter consists of the open triangular ornament formed by the inclined lines, which cross each other about centrally and have their upper portions connected. In the Z the upper left-hand portion is ornamented by the 50 short inclined line.

The character of the design is preserved in the lower-case and numerals.

Having now described my invention, I claim—

The design for a font of printing-type, as 55 shown and described, the same consisting of an unshaded extended letter, the central ornament of the A consisting of the two inclined lines extended beyond the up and down portions and meeting at a central point, the lower 60 right-hand portion of the B, K, and R extended above the upper right portion of the letter and joined upon the left by a short inclined line, the upper right-hand termination of the C and G consisting of the short inclined 65 line extending above and below the upper portion of these letters, the upper right-hand portion of the E, F, and K ornamented by the short inclined line extending below the upper portions of the letters, the lower right portion 70 of the E, L, and Z followed by the short inclined line extending above and below this portion of the letters, the central ornament of the H consisting of the two short inclined lines crossing each other about centrally, the lower 75 left-hand portion of the J widened at its upper termination and crossed by the short inclined line, the connecting portion of the M consisting of the two inclined lines forming about centrally the open triangular ornament, 80 the lower right-hand portion of the N ornamented by the short inclined line, the tail of the Q consisting of an inclined line with short inclined line at each end, one (the left) below and the other (the right) above the line, in the 85 S both the inclined-line terminations extended above and below the portions of the letter they ornament, in the W the central portion of the letter consisting of the open triangular ornament formed by the inclined lines, which 90 cross each other about centrally and have their upper portions connected, the upper left-hand portion of the Z ornamented by the short inclined line, and the character of the design preserved in the lower-case and numerals.

CHAS. H. BEELER, JR.

In presence of—
HARRY HOOVER,
HERMAN METIUS.
